WASTE RETAINER FOR JOURNAL BOXES

Francis B. Lewis, Omaha, Nebr., and John A. Schroeder, Denver, Colo.

Application August 30, 1943, Serial No. 500,576

2 Claims. (Cl. 308—89)

This invention relates to waste retainers for use in standard railway journal boxes of the plain bearing type having a brass and a wedge which is retained by stop-lugs at the top front corners of the box.

Oil soaked waste is customarily packed under the journal, and unless restrained will sometimes roll out of place. Various retainers have been proposed, but none has proved entirely reliable. The improved retainer hereinafter disclosed is based on a study of the rolling action of the waste and operates to suppress the trouble at its origin.

Rolling of waste almost invariably starts at the inner end of the journal next the dust guard and proceeds from there outward, the entire body of waste finally rolling into the interval between the end of the journal and the lid of the box, and forcing the lid open. If the rolling tendency can be suppressed where it starts, close to the dust guard, success is assured. The present invention gives restraint over the entire top of the mass of waste so that it is evenly maintained, but the critical point is the inner end along the sides of the journal.

Hence the retainer becomes essentially a plane grid which overlies the waste over the entire superficial area, nearly to the dust guard, and this grid is substantially rigid. The grid is held in and down by two bow springs which react so as to urge the grid down clear to the inner end of the journal. The springs react against the wedge stop-lugs, so that a rigid spring seat is had, and vibration and weaving motion are minimized.

Like most prior art retainers this one can be formed of a single length of spring wire and is so shown, but this is not the vital novel feature. The vital thing is a grid of adequate area and of length sufficient to react close to the dust guard. Equally important is adequate spring reaction in the correct direction. Bowed springs at the front corners of the grid afford this, and have the important incidental advantage that they are so located as to permit easy inspection of the interior of the box.

For purpose of explanation the preferred embodiment will now be described by reference to the accompanying drawings. In the drawing:

Figure 1 is a vertical axial section of a standard journal box with the improved retainer in place.

Figure 2 is a perspective view of the retainer as it appears prior to insertion in the box.

The body of the box is indicated by the nu-

meral 6. The journal appears at 7, the brass at 8, the wedge at 9, the slot for the dust guard at 10, and the wedge stop lugs at 11. The lug 12 receives the hinge pin for the box lid (not shown). The cellar of the box is packed with oil soaked waste 13.

All the parts so far described are standard in the railway art.

The waste retainer which is shown in place in Fig. 1 and removed in Fig. 2 comprises a flat base of grid form made up of two pairs of parallel bars 14 and a zigzag cross section 15. The bars 14 are connected in pairs by loops at their rear ends and are offset and welded together at 16. At the forward corners are outstanding spring arms 17 which are bowed rearwardly at 18 and terminate in hooks 19 which ensure proper engagement with the wedge stop-lugs 11, as indicated in Fig. 1.

10 20 15 25 30 The bars extend nearly to the inner end of the journal 7 and are effective to hold the waste down. Two such bars as shown are ordinarily sufficient. The zigzag connection 15 gives a good hold down effect at the front of the journal. The reaction of the springs 17 is adequate and correct in direction.

The retainer is easy to insert and remove and since the springs 17 are at the sides of the box the retainer need not be removed to inspect the 30 box.

It is not essential that the retainer be constructed of wire, or that the precise form illustrated be slavishly adhered to.

What is claimed is:

35 1. A waste retainer for waste-packed plain journal boxes of the type having projecting means at the top front of the box, said retainer comprising a substantially flat grid-like base adapted to overlie the waste over substantially the entire U-shaped interval between the sides and end of the journal and the sides and front of the box; and a pair of bowed spring arms which extend upward and inward from the forward corners of said base and are formed to engage said projecting means and react thereupon to urge the base inward and downward.

40 45 50 55 2. A waste retainer for waste-packed plain journal boxes of the type having wedge stop-lugs at the top front of the box, said retainer comprising a flat grid-like base including two pairs of bars, the bars of a pair being spaced but connected at both ends, each pair extending substantially the full length of the journal on respective sides thereof, with a zigzag cross connection between the two pairs approximately

spanning the interval between the end of the journal and the front of the box; and a pair of bowed spring members which extend upward and inward at opposite sides of the front end of said base, and are formed to engage respective wedge stop-lugs and react thereupon to urge the base inward and downward. 5
